UNITED STATES PATENT OFFICE.

JACOB L. BROSCHART, OF TRENTON, MISSOURI.

PIPE-CO尤PLING.

1,303,848.

Specification of Letters Patent. Patented May 20, 1919.

Application filed October 4, 1918. Serial No. 256,880.

To all whom it may concern:

Be it known that I, JACOB L. BROSCHART, a citizen of the United States, residing at Trenton, in the county of Grundy, State of 5 Missouri, have invented a new and useful Pipe-Coupling; and I do hereby declare the following to be a full, clear, and exact description of the invention, such as will enable others skilled in the art to which it applies

10 pertains to make and use the same.

This invention relates to the art of couplings, and particularly to a type especially adapted for use in connection with train or steam lines of passenger or freight trains.

15 Heretofore, when a train line becomes broken at any location the car having the severed or broken portion of the train line becomes dead, in so far as the proper operation of the air brakes are concerned, consequently it is necessary to set the car out on a siding or set it to the rear of the train, so that the air brakes may operate, and so that the train line may carry 95 or 100% air.

20 Heretofore in case of engine failure, there is considerable expense, labor and danger involved in getting the train to its terminal, or to some repair place, where the engine failure may be remedied. The expense involved in getting a train to its terminal after 25 engine failure aggregates approximately \$100 every 24 hours, and to move a train after engine failure, which results in the air brakes being inoperative, it is exceedingly dangerous particularly going down grade. In 30 case of car failure, or should a car become a non-air car, the expense in finally getting the car to its terminal would approximately be \$7 or \$8 every 24 hours.

35 Therefore, in general it is the aim of the present invention to overcome these foregoing difficulties and disadvantages, by providing an emergency device of this kind, whereby the train or steam line of the train may be temporarily repaired at any location 40 it may become broken, so that the train may continue on to its terminal, where permanent repairs may be made.

45 Further, it is the aim to equip each and every train with one or more of the present 50 emergency couplings, with which a train line, either at the angle cock or the T, or at the usual or common coupling of the train line, or at any location in the cross-over connection, may be easily and quickly temporarily repaired, the repairs requiring little

or no time, to put the train or steam line into service.

Specifically, a further object of the invention is to provide an improved, simple, efficient and practical compound coupling, 60 which may be used single or double, for uniting the adjacent ends of a broken pipe or for uniting two sections of piping either of the same or different diameters.

A further object of the invention is to 65 provide an emergency coupling having expandable members or rings and packings, the packing being constructed of any suitable material preferably rubber.

Should the steam line become broken, it 70 may be easily and quickly repaired by employment of the emergency coupling, by substituting steam resisting gaskets in lieu of the rubber gaskets. However, should the occasion require, a section of a hose gasket 75 may be cut out, thereby allowing the gasket to be used in lieu of the rubber packing, in order to facilitate the repair to the steam line.

A further object of the invention is to 80 provide a coupling of this kind including metallic packing members, which may be expanded or contracted in order to bulge, jam or expand the rubber or steam resisting packings, in order to render the coupling 85 efficiently secure whereby a non-air car may be allowed to remain in its proper place in the train, thereby allowing the train to reach its destination without setting the non-air car to the rear.

90 A further object of the invention is to provide metallic expandable packing rings or members, one or both ends of which may be expanded, to lock the coupling secure.

A further object of the invention is to 95 provide sectional metallic expandable rings, and means for holding the sections in their proper positions when expanded.

Further it is the aim to improve simplify 100 and render more practical and useful the structure of coupling, set forth, illustrated and claimed in the application of Jacob L. Broschart, for a patent on a pipe coupling, filed March 8, 1918, Serial No. 221,163, which is matured into patent issued 15th day of October, 1918, Patent No. 1,281,905.

105 In practical fields the details of construction may necessitate alterations falling within the scope of what is claimed.

110 The invention comprises further features

and combination of parts as hereinafter set forth, shown in the drawings and claimed.

In the drawings:—

Figure 1 is a view in side elevation showing the conventional form of train line, which should the same become broken at any location from angle cock to angle cock, or in the cross over connection, may be easily and quickly repaired by the present form of 10 emergency coupling.

Fig. 2 is a view in side elevation of the improved emergency coupling constructed in accordance with the invention.

Fig. 3 is a view in side elevation of the 15 train line, illustrating three different breaks in the line as having been repaired by use of the emergency coupling, one break being made in the cross over connection.

Fig. 4 is an enlarged detail sectional view 20 on line 4—4 of Fig. 3, showing the break in the train line adjacent the common coupling therein as having been repaired, showing one form of metallic expansible packing members.

Fig. 5 is an enlarged detail perspective 25 view of one of the metallic expansible packing members shown in Fig. 4.

Fig. 6 is an enlarged detail view in side 30 elevation of the improved coupling illustrating another form of expansible metallic packing rings or members, the same being constructed in sections, and means for expanding such rings.

Fig. 7 is a longitudinal sectional view 35 through the broken parts of a train line adjacent the common coupling therein, showing the severed ends of the train line as being temporarily united or coupled by the device shown in Fig. 6.

Fig. 8 is a cross sectional view on line 8—8 of Fig. 6.

Fig. 9 is a longitudinal sectional view of 40 the emergency coupling employed for uniting the broken sections of a train line, adjacent the common coupling.

Fig. 10 is a view in side elevation of the coupling shown in Fig. 9, showing a modified form of metallic expansible packing member.

Fig. 11 is a detail perspective view of one 50 of the expansible metallic members shown in Figs. 9 and 10.

Fig. 12 is a longitudinal sectional view of another form of coupling, in which the metallic and rubber filler or packing members 55 are contracted, to bind in contact with the pipe sections to be united.

Fig. 13 is a view in side elevation of the coupling shown in Fig. 12, showing a portion 60 thereof in section and illustrating another application.

Fig. 14 is a detail perspective view of the form of contracting metallic packing shown in Fig. 12.

Referring more especially to the drawings

1 designates that portion of a train line carried by a single car of a train which portion may become broken adjacent either of the angle cocks 2 as at the location indicated by the numeral 3, or adjacent the common coupling 4 at the locations 5 and 6. The train line may become broken adjacent either end of the T 9, as at 7 and 8. The cross over connection of the train line may also become broken, either at 10, 11, 12, 13 and 14. 75 It is obvious that should the train line become broken at any one of these locations, the same may be easily and quickly temporarily repaired by any of the couplings shown in the other figures, for instance as 80 shown in Figs. 3 and 4.

Referring to Figs. 2, 3 and 4, it is to be noted that the coupling comprises a pipe or tubular section 15 exteriorly threaded throughout its length, and in Fig. 4 16 and 85 17 denote the broken parts of the train line. Threaded on the pipe or tubular section 15 adjacent both ends thereof are collars or rings 18 and 19, which are locked against rotation by the keys 20. Surrounding the 90 pipe or tubular section 15 and adjacent said collars 19 are expansible packing members 21 and 22. Also surrounding the tubular or pipe section are the metallic bands 23 and 24 the adjacent ends of which are tapered 95 as shown at 25 and 26. These metallic bands or rings are arranged adjacent the expansible rubber packings so that when they are forced toward the packings, said packings will be expanded toward and in 100 contact frictionally with the inner wall of the broken train line sections 16 and 17. Also threaded upon the tubular or pipe section 15 are jamming or locking sleeves 27 and 28, the adjacent ends of which are provided with nut heads 29. The other ends of the sleeves are tapered as shown at 30. Interposed between the jamming or locking sleeves 27 and 28 and the metallic bands or rings 23 and 24, and surrounding the pipe 105 or tubular section 15 are rings 31 and 32, which may be any suitable shape, preferably as shown, and are provided with spring arms 33. The ends of the arms 33 are flared or turned outwardly into sharpened corners or edges 34, adapted to bite into the inner wall of the train line sections 110 16 and 17. In order to unite the adjacent severed ends of the train line sections 16 and 17, the foregoing parts are arranged as shown in Fig. 4, and by setting up the jamming or locking sleeves 27 and 28, so as to move from each other, the rings 31 and 32 will be moved in the direction of the metallic bands 23 and 24. These bands 115 23 and 24 will in turn be forced toward the rubber packings 21 and 22 causing them to expand frictionally in contact with the inner walls of the train line sections 16 and 17. At the same time that the metallic 120

130

bands 23 and 24 are forced toward and jamming the packings, the spring arms 33 of the rings 31 and 32 will be expanded causing their sharpened edges 34 to bite 5 into the inner wall of the train line sections 16 and 17 thereby locking the coupling parts secure. In Figs. 6, 7, 8, 9 and 10, modified forms of metallic expansible rings 10 or members are illustrated. In Figs. 6, 7 and 8 the expansible metallic rings 35 are circular, and each consists of two semi-circular sections 36, which surround the pipe or tubular section 15. The opposite edges of each ring 35 are turned or flared 15 outwardly, and are substantially sharp, so as to bite into the inner wall of the train line sections 16 and 17, as shown at 37. The sections 36 of the ring 35 are provided with grooves 38 for the reception of expansible 20 split round rings 39, to hold the sections 36 in place as they are expanded. In Figs. 6, 7 and 8 the tapered portions 30 of the jamming or locking sleeves 27 and 28 substantially correspond to the tapered parts 25 of the bands 23 and 24, so as to extend into the rings or bands 35. Referring to Figs. 6 and 7 it is obvious that by screwing up the jamming or locking sleeves 27 and 28, that is from each other, their tapered 30 portions 30 will move the rings or bands 35 toward the bands 23 and 24 expanding the packings 21 and 22, and at the same time expanding the sections 36 of the rings or bands 35, thereby coupling or uniting the 35 two sections of the train line. In Figs. 9 and 10 the metallic expansion rings or bands 40 are split diagonally as shown at 41, so as to expand or contract, as a result of loosening or tightening up the jamming or locking sleeves 27 and 28. These metallic expansion rings or bands 40 have their opposite ends provided with sharpened out-flared edges 42, to bite into the inner wall 40 of the train line sections 16 and 17.

In Figs. 12 and 13 the coupling comprises an outer casing 43, one end of which has an internal shoulder 44, and adjacent the shoulder is a ring 45 having spring arms 46 provided with end sharp edges 47, which 45 are designed to bite into the outer wall of the coupling sleeve 48, which unites the pipe sections 49 and 50, by means of the threaded connections 51 and 52. Arranged adjacent the sharpened end edges of the arms 46 is a metallic ring 53, so beveled as to force the sharpened edges into the coupling sleeve. Also surrounding the coupling sleeve 48 and located within the case is a metallic ring 54, which is also beveled similar to the ring 53, 55 and interposed between the rings 53 and 54 is a rubber expansible packing 55, which by means of the bevels of the rings 53 and 54 is contracted inwardly toward and in frictional contact with the sleeve 48. Additional metallic rings 56 and 57 are arranged

in the casing 43, and which are also beveled. Interposed between the rings 56 and 57 is a rubber packing 58, which, owing to the opposed bevels of the rings 56 and 57, is contracted toward and in contact with the pipe section 50. Arranged in the casing 43 is a metallic ring 59 having spring tongues or arms 60, which, by contacting with the bevel of the ring 57, are contracted or deflected inwardly, so as to bite into the pipe 75 section 50. Surrounding the pipe section 50 and threaded into the casing 43 is a jamming or locking sleeve 61, which abuts the ring 59, whereby the spring arms or tongues 60 may contact with and be deflected by the bevel of the ring 57. By screwing the jamming sleeve, the several rings may be forced toward the shoulder 44 thereby contracting the rubber packing members 49 and 50. One end of the jamming sleeve 63 has a nut head 80 62, and a threaded cavity 63, into which an inch and a quarter pipe or tube 64 of a train line of a passenger train is threaded. It is obvious that instead of inserting a pipe section 49 with the coupling sleeve 48 90 into the coupling shown in Fig. 12, an inch and a quarter pipe 65 of the train line of the passenger train may be inserted into the coupling, (which is shown in Fig. 12) and telescopically over a short pipe section 95 66, as shown in Fig. 13. The spring arms or tongues 60 have sharpened end edges 67, in order to bite into the pipe section 50 of the train line.

Referring to Fig. 1 of the drawings, it is 100 to be noted that should the train line break as at 3 at the left hand end in Fig. 1, the angle cock 2 may be removed, and an ordinary elbow 68 coupled to the usual air hose 69 as shown in Fig. 3. In this case the end 105 70 of the pipe or tubular section 15 is threaded into the lock sleeve 71, while the other end of the emergency coupling, as indicated at 72 is inserted into the portion 73 of the train line, thereby temporarily splicing the 110 train line, whereby the train may continue to its terminal after which permanent repairs may be made. Should the train line break at 5 or 6, for instance 5, the opposite ends of the emergency couple may be inserted into the severed ends of the train line, as shown clearly at 74 in Fig. 3, and also as shown in Fig. 4, thereby temporarily uniting or splicing the train line, to allow the train to continue to its terminal. Should 115 the cross over connection become broken as at 13, one end 75 as shown in Fig. 3 may be inserted into the broken parts of the cross over, that is after removing the cross over valve 76, the auxiliary reservoir 77 and 120 the air cylinder 78. When inserting one end of the coupling into the cross over connection as shown in Fig. 3, a cap 79 is threaded to one end of the tubular or pipe section 15, thereby holding 85% air in the train line. 130

- Should a break occur in the cross-over adjacent the auxiliary reservoir, the cross over valve 76 may be closed, and in this case the coupling would not be used. Also should the cross over connection break at 14, the cross over valve 76 may be closed, in which case the use of the coupling would be avoided. Should the train line break at 7 or 8 as shown in Fig. 1, the train line may be repaired in the same manner as when the train line is broken either at 5 or 6. However, should the cross over connection become broken either at 10, 11 or 12, one end of the coupling is inserted either in the tubular leg of the T 9 or in the elbow 80, just sufficiently to permit one of the expansion packing rings 21, or 22 to be expanded into the broken part of the cross-over connection, that is the broken part which is allowed to remain in the leg or the elbow, then the other end of the coupling is inserted into the opposite severed parts of the cross-over, thereby temporarily repairing the train line system.
- 25 The invention having been set forth what is claimed as new and useful is:—
1. In an emergency coupling, the combination with the adjacent ends of a broken pipe, of a pipe section exteriorly threaded throughout its length, a lock collar on each end of said section, a band surrounding said section and spaced from the collar, and an expansible packing between the band and the collar, a jamming sleeve threaded on the section, a ring interposed between the sleeve and the band, said ring having expansible means adapted to expand to bite into the interior wall of one of said ends, when the jamming sleeve is turned home.
  - 40 2. In an emergency coupling, the combination with the adjacent ends of a broken train line pipe, of a tubular pipe section exteriorly threaded throughout its length and telescoping the adjacent ends in spaced relations to their interiors, a holding member on each end of the pipe section, a band on the pipe section spaced from the member, a jamming sleeve threaded on the pipe section and telescopingly fitting into one of said ends, metallic expansible means interposed between the jamming sleeve and the band and provided with biting parts to bite into said end when the jamming sleeve is turned home, and an expansible packing between the band and the holding member, and adapted to be expanded by the actions of the sleeve and the metallic means.
  - 55 3. In an emergency coupling, the combination with adjacent broken end parts of a train line pipe, of a tubular pipe section exteriorly threaded throughout its length, and one end or the other adapted to extend telescopically in spaced relation into one of said end parts, an expansible packing surround-
  - 60 ing the inserted end of the pipe section, spaced holding members for said packing, one adjacent each side thereof, a jamming sleeve threaded on the pipe section and telescopically fitting in the said end part, a metallic element surrounding the pipe section and co-operating between one of the holding members and the jamming sleeve, said element having expansible means actuated by the co-acting functions of the sleeve and one of said holding members, said expansible means having biting parts to engage the interior wall of one of the end parts of the train line pipe when the expansible means is expanded, thereby splicing the adjacent ends of the train line pipe.
  - 65 4. In an emergency coupling, the combination with adjacent broken end parts of a train line pipe, of a tubular pipe section exteriorly threaded throughout its length, and one end or the other adapted to extend telescopically in spaced relation into one of said end parts, an expansible packing surrounding the inserted end of the pipe section, spaced holding members for said packing, one adjacent each side thereof, a jamming sleeve threaded on the pipe section and telescopically fitting in the said end part, a metallic ring co-operatively interposed between the jamming sleeve and one of the holding members, said ring having a continuous expansible portion, adapted, when the sleeve is turned home to bite into said end part of the train line pipe, thereby temporarily splicing the broken parts of the train line pipe.
  - 70 5. In an emergency coupling, the combination with adjacent broken end parts of a train line pipe, of a tubular pipe section exteriorly threaded throughout its length, and one end or the other adapted to extend telescopically in spaced relation into one of said end parts, an expansible packing surrounding the inserted end of the pipe section, spaced holding members for said packing, one adjacent each side thereof, a jamming sleeve threaded on the pipe section and telescopically fitting in the said end part, a metallic ring co-operatively interposed between the jamming sleeve and one of the holding members, the opposite end edges of said ring having biting portions to bite into said end part of the train line pipe, said ring being split diagonally, whereby it may be expanded by the co-operative actions of the sleeve and said holding member, whereby the biting portion may engage the end part of the train line pipe for temporarily splicing the broken parts of the train line.
  - 75 6. In an emergency coupling, the combination with adjacent broken end parts of a train line pipe, of a tubular pipe section exteriorly threaded throughout its length, and one end or the other adapted to extend telescopically in spaced relation into one of said end parts, an expansible packing surround-

ing the inserted end of the pipe section, spaced holding members for said packing, one adjacent each side thereof, a jamming sleeve threaded on the pipe section and telescopically fitting said end parts, a metallic expandible ring coöperatively interposed between the jamming sleeve and one of said holding members, said holding member and the jamming sleeve having means to expand the expandible ring, said expandible ring having biting end edges to bite into the end part of the train line pipe when the jamming sleeve is turned home, thereby temporarily splicing the broken parts of the train line.

7. In an emergency coupling, the combination with adjacent broken end parts of a train line, of a tubular pipe section, one end or the other adapted to extend telescopically in spaced relation into one of said end parts, an expandible packing means surrounding the pipe section and engaging the interior wall of the broken end part of the train line, holding means for the packing means, a part of said holding means being tapered, a jamming sleeve threaded on the pipe section and telescopically fitting said end parts, a metallic ring coöperatively interposed between the holding means and the jamming sleeve, said ring being expandible and provided with opposite continuous biting portions to be expanded by the tapered part of the holding means, whereby said portions may bite the interior wall of the train line by the coöperative actions of the sleeves and the holding means, thereby temporarily splicing the broken parts of the train line.

20 In testimony whereof I have signed my name to this specification in the presence of two subscribing witnesses.

25

30

the end part of the train line by the coöperative actions of the sleeve and the holding means, thereby temporarily splicing the broken parts of the train line.

8. In an emergency coupling, the combination with adjacent broken end parts of a train line, of a tubular pipe section, one end or the other adapted to extend telescopically in spaced relation into one of said end parts, an expandible packing means surrounding the pipe section and engaging the interior wall of the broken end part of the train line, holding means for the packing means, a part of said holding means being tapered, a jamming sleeve threaded on the pipe section and telescopically fitting said end parts, a metallic ring coöperatively interposed between the holding means and the jamming sleeve, said ring being expandible and provided with opposite continuous biting portions to be expanded by the tapered part of the holding means, whereby said portions may bite the interior wall of the train line by the coöperative actions of the sleeves and the holding means, thereby temporarily splicing the broken parts of the train line.
